UNITED STATES PATENT OFFICE.

HORACE H. TAYLOR, OF OAKLAND, CALIFORNIA.

PUMP.

1,410,520.

Specification of Letters Patent. Patented Mar. 21, 1922.

Application filed February 7, 1921. Serial No. 442,933.

To all whom it may concern:

Be it known that I, HORACE H. TAYLOR, a citizen of the United States, residing at Oakland, in the county of Alameda and State of California, have invented new and useful Improvements in Pumps, of which the following is a specification.

The present invention relates in general to improvements in pumps, particularly wa-
ter pumps.

The primary object of the invention is to provide a comparatively simply constructed, small, compact pump which is capable of ready and easy assembling and disassembling and will have a greater capacity for pumping and provide a maximum pumping action more expeditiously and economically than the ordinary pump.

Another object of the invention is to pro-
vide in a pump of the character described, novel, reliable and effective means for transmitting the rotary motion from a prime mover to a series of reciprocal pumps, said means and the pump being so constructed
and compactly arranged that more than the ordinary number of pumps may be employed and operated effectively, reliably and economically to provide a maximum pumping action both as to volume and rate of flow, it being also provided by such arrangement that ready access may be had to the parts of the pump for the purpose of inspection, repair or renewal of said parts.

A further object is to provide a novel valve construction and valve arrangement for a pump of the character described whereby little or no room is taken up by the valves and a saving in space is provided as well and a gain in the efficiency of valvular operation and the pump as a whole is consummated.

The invention possesses other advantages and features some of which, with the foregoing will be set forth at length in the following description where I shall outline in full that form of the invention which I have selected for illustration in the drawings accompanying and forming a part of the present specification. In said drawings I have shown one form of the construction of my invention, but it is to be understood that I do not limit myself to such form since the invention as expressed in the

claims may be embodied in a plurality of forms. 55

Referring to the drawing, the figure represents a vertical sectional view of the pump of this invention.

In carrying out the invention there is pro-
vided as shown in the accompanying draw-
ing, a pump casing or housing 1 having an
intake connection 2 and an outlet or dis-
charge connection 3. The housing prefer-
ably includes a base section 4 which carries
the intake connection 2 and is bolted as at 5
5 to a super-imposed pump cylinder section
6. A body or intermediate section 7 is bolted
at 8 to the upper side of the cylinder
section 6 and carries the outlet or discharge
connection 3. A head section 9 is bolted as 65
at 10 onto the upper side of the interme-
diate or body section 7. A hand hole plate
10' is provided on the base section 4 and is
secured thereto by bolts 11. Other hand
hole plates not shown may be provided as 70
desired.

Extending into the housing through a bearing 12 in an offset portion 13 of the head section 9 is a drive shaft 14 which is driven from a motor or other suitable prime 80
mover (not shown). A bearing 15 receives the inner end of this shaft within the off-
set portion. A pinion 16 is keyed upon the
shaft and meshes with a large spur gear 17
keyed upon an upright main shaft 18. The 85
shaft 18 is journalled at its ends in bear-
ings 19 and 20 provided at opposite central
points of the intermediate and head sec-
tions of the housing said gear 17 being dis-
posed within the head section. 90

Associated with and operated by the shaft 16 is means generally designated 21 for transforming the rotary movement to reciprocatory movement and operating a plurality of independent pump mechanisms 22 95
which latter are carried in the sections 6 and 7.

The means 21 comprises a collar 23 loosely surrounding the shaft 16 just below the gear 17. The collar is provided with radially 100
extending apertured ears 24. Pivoted as at 25 in these ears are substantially L shaped
bell cranks 26. The collar is connected by
spaced webs 27 with an annular support 28
fitted nonrotatably but removably in the up- 105
per end of the housing section 7 and the

bell cranks operate in the slots or spaces between said webs. The lower ends of the bell cranks are slidably engaged with an eccentric member 29 keyed to the shaft 16. The 5 eccentric comprises a circular disc 30 eccentrically mounted on the shaft and provided on its upper side with an annular groove 31, the groove being semi-circular in cross section. The lower ends of the bell cranks 10 have reduced screw-threaded extensions 32 which turn into sockets 33 formed in bearing balls 34. The balls 34 are thus removable and may be easily replaced when worn. These balls slidably engage in the groove 31 15 and are held in place by an annular plate 35 secured by fastenings 36 to the upper side of the disc 30. At the periphery of the plate 35 is provided an annular upstanding flange 37 having a curved ball engaging face 20 37'. As the eccentric 29 rotates the balls 34 slide in the groove 31 and the bell cranks are rocked on their pivots.

Links 38 join the upper ends of pump piston rods 39 with the upper ends of the bell 25 cranks and said rods 39 are slidable through lubricating bushings 40 carried in the upper wall 41 of the housing section 7. This wall serves as a fluid tight seal between the sections 7 and 8 and confines the fluid being 30 pumped to the section 7 whereby said fluid will discharge through the outlet connection 3. The bushings 40 serve as stuffing boxes. The rods 39 extend into pump cylinders 42 arranged in arcuate formation in the section 35 6 of the housing. The cylinders are open at both ends and hollow pump pistons 43 are attached to the rods 38 and are reciprocally mounted in said cylinders. As many as nine or twelve, of the cylinders, or 40 better, individual pumps may be provided, in fact, any number as desired may be used.

The hollow pistons are each provided with a lower end wall 44 having an intake port 45 therein. The upper side of each piston 45 is open and provided with an annular valve seat 46 upon which seat an annular upwardly opening check valve 47 engages so as to control the passage of the fluid through the pistons. Check valves 48 are slidable 50 upon the rods 39 and seat upon the upper ends of the cylinders 42. Springs 49 surround the rods 39, abut the valves 48 and bushings 40 so as to normally hold the valves in closed position.

55 A vacuum chamber 50 is provided centrally in the section 6 of the housing and opens on the lower side of said section into the base section of the housing. A bracing stud 51 is mounted between and abuts opposed central portions of the sections 6 and 7 of the housing. The intake connection 2 includes a passage 52 which extends first upwardly and then downwardly so as to provide a trap within the base section 4 of 65 the housing, whereby, sufficient liquid is at

all times maintained in the base section to eliminate the necessity of priming the pump.

Operation.

When the shaft 18 is rotated the eccentric 70 revolves and causes the bell cranks to rock. This reciprocates the rods 39 and pistons 43 attached thereto so as to quickly and reliably effect the pumping action in cycles in the several pumps. As each piston is drawn 75 upwardly opening check valve 47 opens the valve and the water is forced through the piston against the valve 48 and the pressure will open said valve 48. The water then passes into the suction 7 and out through 80 the outlet connection 3. This action takes place in each pump and it will be seen that upon each revolution of the main shaft an effective and thorough pump action is provided. In the event that one or more of 85 the pumps become inoperative the other pumps will function without interference in the normal manner and in this way the serviceability and reliability of the pump will be greatly increased. 90

I claim:

1. A pump of the character described, embodying in its construction a housing having an intake and an outlet, a plurality of pump cylinders within the housing and disposed between said intake and outlet, a main shaft journalled in the housing, an eccentric on the housing, bell cranks pivoted within the housing and having certain ends mounted in the eccentric, piston rods, pistons on said rods reciprocally mounted in the cylinders said pistons having passages extending therethrough, and upwardly opening check valves normally closing the upper ends of said cylinders. 95

2. A pump of the character described embodying in its construction a housing and an intake and an outlet, a plurality of independent pumps mounted within the housing and arranged so that the cylinders and pumps establish connection between portions of the housing in which the said intake and outlet are provided, a main drive shaft mounted within the housing means for rotating said shaft, a plurality of pump pistons reciprocal within the cylinders and each having a passage therethrough, an upwardly opening check valve normally closing the upper ends of said cylinders and means of operative connection between each piston and said shaft including an eccentric member fixed to and rotated by the shaft. 110

3. A pump of the character described embodying in its construction a housing and an intake and an outlet, a plurality of independent pumps mounted within the housing and arranged so that the cylinders and pumps establish connection between portions of the housing in which the said intake and outlet are provided, a main drive shaft 125 130

mounted within the housing means for rotating said shaft, a plurality of pump pistons reciprocal within the cylinders and each having a passage therethrough, an upwardly

5 opening check valve normally closing the upper ends of said cylinders and means of operative connection between each piston and said shaft including an eccentric member fixed to and rotated by the shaft, and
10 bell cranks pivoted within the housing and arranged to be rocked upon rotation of the eccentric and piston rods connected with said rocker arms and said pistons.

4. A pump of the character described embodying in its construction a housing comprising a base section having an intake connection, a pump cylinder section mounted upon said base section, a plurality of independent pump cylinders in said last named 20 section opening into the base section, an intermediate section mounted upon and secured to the pump cylinder section said pump cylinders opening at their upper ends into said last named section, a head section 25 mounted upon and secured to the last named section, a partition in the intermediate section closing off communication between the head and intermediate sections, said intermediate section having an outlet therein a 30 rotary shaft mounted in the head section, an eccentric fixed to said shaft, a plurality of bell cranks pivoted at the head section and having said ends slidably connected with said extensions, pinions reciprocal in the 35 cylinders and having passages extending therethrough, check valves controlling said passage, an upwardly opening check valve normally closing the upper end of each cylinder,

der, and piston rods pivotally connected with the other ends of said bell cranks and with 40 said pistons and extending through said piston.

5. A pump of the character described embodying in its construction a housing comprising a base section having an intake connection, a pump cylinder section mounted upon said base section, a plurality of independent pump cylinders in said last-named section opening into the base section, an intermediate section mounted upon and secured to the pump cylinder section said pump cylinders opening at their upper ends into said last named section, a head section mounted upon and secured to the last named section, a partition in the intermediate section closing off communication between the head and intermediate sections, said intermediate section having an outlet therein a rotary shaft mounted in the head section, an eccentric fixed to said shaft, a plurality of 60 bell cranks pivoted at the head section and having said ends slidably connected with said extensions, pinions reciprocal in the cylinders and having passages extending therethrough, check valves controlling said 65 passage, an upwardly opening check valve normally closing the upper end of each cylinder, and piston rods pivotally connected with the other ends of said bell cranks and with said pistons and extending through said 70 piston, a spur gear fixed to said shaft a pinion meshing with said spur gear and disposed within the head section and means for rotating said pinion adapted for connection with a prime motor.

HORACE H. TAYLOR.
